UNITED STATES PATENT OFFICE

CHARLES ROY HUNTER AND ROBERT M. PIERCE, OF LOS ANGELES, CALIFORNIA,
ASSIGNORS TO UNIVERSAL PICTURES CORPORATION, OF UNIVERSAL CITY, CALI-
FORNIA, A CORPORATION OF NEW YORK

FILM PROCESSING MACHINE AND METHOD

Application filed October 16, 1931. Serial No. 569,162.

This invention relates to machines for, and methods of, treating photograph films, and particularly films in the form of elongated tapes such as are used in motion pictures.

5 An object of this invention is to provide a commercially successful method of producing duplicate negatives or positive motion picture films by the inversion process.

It is common photographic practice to de-
10 velop an exposed film by converting the ma-
terial in the film that has been acted upon by
light, into dark or opaque substance. Hence
the film, after development, is a negative;
that is to say, the light portions of the origi-
15 nal scene show dark in the film and the dark
portions of the original scene show light in
the film. It is the practice to then prepare
final prints from the negative by expos-
ing the sensitive film to light transmitted
20 through the negative and developing the
print in the same general manner as the
original negative was developed. Since the
image in the negative is a reversal of the ac-
tual image and the image in the final print
25 is a reversal of the image in the negative,
there have been two reversals, thus making
the final print similar to the original image,
or a "positive" as it is commonly termed.

The above method of producing prints of
30 motion picture film is disadvantageous in that
all of the final prints must be taken from the
original negative, or a plurality of negatives
must be made by printing from a positive
made from the original negative. The first
35 method is objectionable because there is a
certain amount of wear on a negative during
the printing process, and this places a defi-
nite limit on the number of satisfactory prints
that can be taken from one negative. By the
40 second process, as many negatives may be
produced as desired, so that there is no need
of taking a greater number of prints from
any one negative than can be satisfactorily
obtained. However, this method is open to
45 the objection that there is a certain loss in
quality during each printing process. In
other words, due to imperfections in the ma-
terial of which films are constructed, a print
from one film never carries quite as perfect
50 an image as did the print from which it was

made. Thus, where a positive print is made
from the original negative and then addi-
tional negatives are made from the positive,
the additional negatives never carry as per-
fect images as did the original negative. It 55
follows, of course, that positive prints made
from the additional negatives are not as good
as positive prints made from the original neg-
atives.

As indicated above, the usual process of 60
treating exposed film, which comprises de-
veloping and fixing, produces a negative
image, that is, one opposite to the original.
Obviously, if the original film were devel-
oped into a positive rather than a negative,
then a large number of negatives could be
produced from the original positive, and since
the production of the negatives would in-
volve only one printing operation, their qual-
ity would be substantially better than that of 70
negatives made as the result of two consecu-
tive printing processes. It has been known
for many years that by utilizing special proc-
esses, a positive image can be produced on a
film. These processes are commonly termed 75
"inversion processes" and may comprise the
following steps:

1. Development	1. Developing
2. Washing	2. Washing
3. Bleaching	3. Bleaching
4. Washing	4. Washing
5. Clearing	5. Clearing
6. Fogging	6. Fogging
7. Re-developing	7. Re-developing
8. Washing	8. Fixing
9. Drying	9. Washing
	10. Drying

It will be noted that the first process listed
above comprises nine distinct operations, 90
and the second process comprises ten distinct
operations, as compared to four in the usual
process, namely: Developing, fixing, wash-
ing and drying.

It is present practice to develop motion 95
picture film by continuous processes in which
the film is passed continuously and suc-
cessively through developing, fixing, washing
and drying chambers.

Prior to applicants' invention, as dis- 100

closed herein, and also in Patent 1,845,416, issued February 16, 1932, to Hunter and Pierce, on application Serial No. 428,729, filed January 27th, 1930, the only machines 5 in commercial use for the continuous development of motion picture films involved the driving of a film through treating tanks at a relatively high speed by a large number of rollers to which power was applied simultaneously. Due to their complexity and to 10 mechanical difficulties, these machines are entirely unsuited for use in developing positive images on films by the inversion process because of the large number of steps involved. 15

As disclosed in the aforementioned patent of Hunter and Pierce, it was discovered that by drawing films horizontally through treating fluids in elongated troughs, more satisfactory 20 results could be obtained at much less expense than with the old type of machine then in general use.

In accordance with the present invention, applicants have discovered that their process, 25 because of its simplicity and the small friction to which the film is exposed, enables them to continuously pass film through the large number of treatments necessary to develop films by the inversion process.

30 Various features of the invention will be made apparent by the following description taken in connection with the accompanying drawings, in which—

35 Figure 1 is a side elevational view of our machine with portions broken away to indicate the operation.

40 Figure 2 is a schematic diagram showing the path followed by the film in traversing the different treating troughs in our machine.

45 Figure 2a is a schematic diagram showing the path followed by the film in traversing the different treating troughs in our machine when using an alternative process.

50 Figure 3 is an elevational view of the rear end of the machine.

55 Figure 4 is a sectional view through one of the troughs of the machine showing the film guide pulleys.

50 Figure 5 is a side elevational view of one of the treating troughs showing the method of attachment of the guide wheels shown in Figure 4.

55 Figure 6 is a sectional view showing the positioning of guide members for guiding the film and maintaining it at the proper depth within the treating troughs.

60 Figure 7 is a sectional view in the plane 7—7 of Figure 4.

60 *First inversion process*

Referring to Figure 1, our machine comprises three troughs arranged in a vertical tier, with a drying compartment positioned 65 above the top trough. Each trough is

divided by a longitudinal partition into two compartments. Thus, referring to Figure 2, which shows the troughs spread out so as to disclose each one in plan view, the upper trough is divided by a central partition 4 to 70 form a trough 5 for a clearing bath and a trough 6 for first developer. A cross partition 7 is provided adjacent one end of the developer trough to form a small container 8 containing a stop solution. The second trough is also divided by a longitudinal partition 9 and a transverse partition 10 into a long trough 11 containing developer solution, a short trough 12 containing bleach, and a short trough 13 containing water or rinsing 75 solution. The lower trough is divided by a longitudinal partition 14 into troughs 15 and 16 containing water. 80

The steps in the process of obtaining a 85 duplicate negative or positive by one process with the use of our apparatus will now be outlined briefly with reference to Fig. 2. Exposed film enters from a magazine 17 into the upper front trough 6 containing developer and during its passage through the 90 length of this trough the image is made visible. This image is, of course, opposite to the image from which the film was printed or exposed. When the negative image is fully developed, the film leaves the end of the developer trough 6 and enters the short trough 8 containing stop solution. Stop solutions 95 are commonly used in photographic work for halting the action of the developer and hardening the gelatine coating. From the stop solution trough 8 the film passes directly down into the trough 13 immediately therebelow, containing water, and during its passage through this trough all developer and stop solution is removed from the film.

100 After leaving trough 13, the film enters the trough 12 containing bleaching solution. Numerous reagents are in common use for bleaching the film. Its purpose is to remove the negative image produced by the developer, and this removal is usually effected 105 by a bleaching reagent which changes the reduced silver forming the dark portions of the developed picture into a silver halid or subhalid. At the time the film leaves the bleaching trough 12 the negative image has disappeared. After leaving trough 12 the film passes down into trough 16 directly therebelow. Trough 16 contains water which

110 washes out the bleaching solution and silver salts previously rendered soluble with which the film became impregnated while passing through trough 12. Just before the film passes down into trough 16 it is exposed to

115 light from a lamp 18, which is commonly termed the "fogging lamp". The light from lamp 18 acts upon the previously unexposed portion of the light-sensitive emulsion in the film which was not developed in trough 6 and bleached out in trough 12. As a result, those

120

125

130

sections of the film which were not originally exposed are exposed by the fogging lamp 18.

In the apparatus disclosed all the treating troughs are open. It is therefore necessary that while films are being treated the room in which the apparatus is located be maintained in total darkness, except for such non-actinic light as the films are insensitive to. It is obvious, however, that the fogging lamp 18 must produce actinic light in order to have the desired effect on the film. In order to prevent light escaping from the lamp 18 from reaching portions of the film prior to or during its passage through troughs 6, 8, 13, 12 and 16, it is necessary to locate the lamp 18 very close to the films in trough 16 and to use a source of light that produces very little heat. It has been discovered that a gaseous discharge lamp utilizing neon or a similar rare gas is peculiarly adapted for use in the present apparatus for the reasons that it produces very little heat and may be located very close to the films in trough 16 without heating them to any appreciable extent. Furthermore, although the light produced from such a lamp is sufficiently actinic to produce the desired fogging effect on the films as they pass immediately thereunder, the actinic power of the light escaping from the lamp 18 is insufficient to fog the film before it reaches the end of trough 16.

After leaving the end of trough 16 the film passes upward and at the same time crosses over (the method of crossing over is disclosed in Figure 3) and enters the upper rear trough 5 which contains a clearing bath. The film, after it leaves the bleaching trough 15 and the washing trough 16 is yellow in appearance and the clearing bath in trough 5, which may be sodium sulphite or bi-sulphite removes this yellow color. The film, after being cleared, goes from trough 5 directly therebelow into the middle rear tray 18 which contains developing solution. This solution may or may not be substantially the same as that used in the original developer in trough 6. Since it is used it develops the image produced by the fogging lamp 18, it is commonly termed "redeveloper." The re-developing of the film in trough 11 develops a visible image which is opposite to that produced by the original development but is similar to the image from which the film was printed. In other words, it is a positive image rather than a negative image. After being re-developed in trough 11 the film passes directly down into the lower rear trough 15 which contains water for removing from the film all traces of developer. After leaving the trough 15 the film passes upward between two downwardly directed air jets 19 and 20, which remove all surplus moisture from the film. The film thereafter continues upward to the drying chamber 21 at the top of the machine and is passed in a circuitous path

through the drying chamber 21, during which time it is exposed to a controlled current of dry air which removes all moisture from the film. The film is then withdrawn from the chamber onto a take-up reel 22.

Since the diagram of Figure 2 is purely schematic, it does not disclose how the film is actually moved through the machine.

Referring again to Figure 1, the film leaves the magazine 17 and passes over a brake pulley 23, thence between a tension pulley 24 and an associated pulley 25, around the tension pulley 24, back of pulley 25, thence through one or more guides 26 to an adjustable submersing pulley assembly 27 which comprises three pulleys 28, 29 and 30. Pulleys 28 and 29 are positioned above the level of the developing solution in trough 6, but pulley 30 is positioned below the surface of the developer. The film, after leaving the guides 26, passes over pulley 28, back over pulley 29, and under pulley 30 into the developing solution. During its passage through the developing trough 6 the film, being submerged in the liquid and being of approximately the same specific gravity as the solution needs very little support. However, to maintain it at the proper level above the bottom of the tank, it passes over numerous guides 31. At the end of the developing trough 6 the film passes under a pulley 32, thence up out of the developing solution over a pulley 33 positioned above the partition 7, and thence down under a pulley 34, the lower side of which is submerged in the stop solution in trough 8. From trough 8 the film passes out over a pulley 35, thence down under a pulley 36, and under a pulley 37 submerged in the washing water in trough 13. The film passes through trough 13, being supported by guides 31 similar to those previously described, and at the end of trough 13 passes under a pulley 38, over a pulley 39 positioned above the partition 10, and thence down under the pulley 40 into the bleaching trough 12. Thence it passes through the bleach, out under a pulley 41 at the exit end thereof, and up and over a pulley 42. From pulley 42 the film passes directly down under a pulley 43 and a pulley 44 into the rinsing trough 16. It is supported in its passage through rinsing trough 16 by guides 31 and at the end of the trough is fogged by the light from lamp 18. At the end of trough 16 it passes under a pulley 45 and then up out of the trough and under a pulley 46 from which it extends crosswise up over the end of the machine and over a pulley 47 down into the clearing bath in trough 5. It passes through trough 5, thence under a pulley 48, over a pulley 49, down and under a pulley 50, and into the rear middle trough 11 containing the re-developer. It is submerged in the re-developer by a pulley 51, and passes to the end of the trough 11, thence under a pulley 52, over a pulley 53 and

down under a pulley 54 into the washing trough 15. It is submerged in the solution in washing trough 15 by a pulley 55, passes through the solution supported by guides 31, 5 thence under a pulley 56 at the end of the trough and a pulley 57 at the end of the machine. Thereafter it passes between the blower nozzles 19 and 20 up over a pulley 58 into the drying chamber 21. In the drying 10 chamber it passes lengthwise through the drying chamber, being supported by pulleys 59, and thence out under a pulley 60, over a constantly driven sprocket wheel 61, which serves to draw the entire length of film from 15 magazine 17 through the machine, and under a pulley 62 onto a wind-up reel 22.

Second inversion process

The inversion process just described corresponds to the first process listed in the introduction of the specification. If the second process is used the apparatus employed is substantially identical to that disclosed in Figures 1 and 2, except that the lower front 20 trough is divided into three sections instead of one.

Thus, referring to Figure 2a, in which the parts corresponding to those in Figure 2 are given the same reference numerals with the 25 suffix "a". The film leaves the magazine 17a and passes through the first trough 6a containing developing fluid. The original image is developed in trough 6a precisely as in the process disclosed in Figure 2. The film 30 is then passed through stop solution in trough 8a, is washed in trough 13a and bleached in trough 12a. After leaving the bleaching trough 12a the film tape, instead of being thoroughly washed, as was done in 35 the first process, is given a short rinse in a trough 16b, and is then passed through a clearing bath in trough section 16c before being fogged. After leaving the clearing 40 bath in trough 16c the film tape is washed a short time in the trough section 16d and is 45 exposed to the light from the fogging lamp 18a. After being fogged the film tape passes through directly to trough 5a, which in this process contains a second developer solution 50 instead of the clearing bath. After leaving the second developer in trough 5a the film tape passes through trough 11a, which contains fixing solution. After being fixed the film tape passes down into trough 15a where 55 it is washed, after which it passes between the dryer jets 19a and 20a and thence up to the dryer compartment 21a where it is thoroughly dried. The film tape is then withdrawn from the dryer compartment 21a onto 60 the take-up reel 22a, precisely as in the first process.

It will be apparent that the pulley equipment for guiding the film tapes through the 65 treating troughs shown in Figure 2a will be identical with that disclosed in Figure 1, ex-

cept that additional pulleys of the type disclosed at 32, 33 and 34 in Figure 1 will be required to guide the film out of trough 16b into trough 16c, and out of trough 16c into trough 16d.

Miscellaneous improvements

In the above description only one film has been traced through the machine. The machine is actually designed to handle simultaneously as many films as can be positioned side by side in the troughs. We have found it convenient to use troughs of such width as to accommodate five tapes of film, but this number may be varied between wide limits, if desired. Thus, Figures 4 and 6 disclose treating troughs of sufficient width to accommodate five tapes of film side by side. Figure 4, discloses how a plurality of pulleys (corresponding to pulleys 35, 36, 37, 46, 47, etc.) are mounted on a common shaft for guiding five films into or out of the fluids in the treating troughs, and Figure 6 discloses the construction of the guides 31 for maintaining the film tapes at the proper depth in the treating fluids while they pass longitudinally therethrough. In Figure 4 the outer wall of the trough 64, a floor of the trough 65 and a center partition 66 are shown constructed of wood with the joints tongued and grooved to prevent leakage of the fluids to be contained. The pulleys 67 are preferably of bakelite and are mounted to rotate freely on a metal or bakelite shaft 68 which is secured by shoulders 69 to the walls 64 and 66 of the trough. The pulleys are maintained in proper separated position by separating bushings 70 and are centered with respect to the trough by bushings 71 which are secured to the shaft 68 by set screws, as shown. As disclosed in Figure 5, the end supports 69 are secured to the top edges of the troughs by screws 72.

The guides 31 disclosed in Figures 6 and 7 are preferably constructed of bakelite and are secured to a crosspiece 73 of rectangular cross section, the ends of which are fastened by screws 74 to the edges of the trough. The guides 31 are constructed in sections and are prevented from turning with respect to the rods 73 because of the rectangular shape of the latter.

It should be noted that both the pulleys 67 and the guides 31 are provided with shoulders 75 which engage the edges only of the film, thus preventing any possibility of the central portion of the film tape becoming scratched.

The manner in which the five film tapes are conveyed from the delivery end of one trough to the entry end of the succeeding trough, is clearly shown in the end view of the machine in Figure 3. The numbers on the pulleys in this view correspond to the numbers given in

Figure 1, so that the paths of the tapes may be readily followed.

We claim:

1. In a machine for developing a positive image on an exposed motion picture film tape by a single, continuous process, a plurality of elongated, shallow reservoirs, means for guiding film tape in substantially a straight line through each reservoir, roller means for guiding said film tape into the first of said reservoirs, roller means for guiding said film tape from each reservoir into the next succeeding reservoir, a drying chamber, means for guiding the film tape from the last of said reservoirs into said drying chamber, and a single, take-up means engaging with the film tape beyond said drying chamber and serving as the sole means for moving the film tape through the machine; said successive reservoirs, in the order in which the film tape passes therethrough, containing developing fluid, washing fluid, clearing fluid, washing fluid, redeveloping fluid, and washing fluid, respectively, and a source of actinic light for illuminating said film tape between said washing and re-developing reservoirs.
2. In a machine for developing a positive image on an exposed motion picture film tape by a single, continuous process, a plurality of elongated, shallow reservoirs, means for guiding film tape in substantially a straight horizontal line through each reservoir, roller means for guiding said film tape into the first of said reservoirs, roller means for guiding said film tape from each reservoir into the next succeeding reservoir, a drying chamber, means for guiding the film tape from the last of said reservoirs into said drying chamber, and a single take-up means engaging with the film tape beyond said drying chamber and serving as the sole means for moving the film tape through the machine; said successive reservoirs in the order in which the film tape passes therethrough containing first developer fluid, washing fluid, bleaching fluid, rinsing fluid, fixing fluid, and washing fluid, respectively, and a source of actinic light for illuminating said film tape during its passage between said clearing fluid and said second developer fluid.
3. In a machine for developing a positive image on an exposed motion picture film tape in a single continuous process, a series of open troughs containing solutions for developing, bleaching, and re-developing said tape, means for continuously drawing said tape through said successive troughs, and a gaseous discharge lamp positioned in close proximity to said moving film at a point in its travel between said bleaching solution and said re-developer solution for fogging said tape as it passes said lamp without fogging it prior thereto.
4. The method of producing a positive

image on an exposed motion picture film tape that comprises drawing the tape successively through a developing liquid, a washing liquid, a bleaching liquid, a second washing liquid, a clearing liquid, a re-developing liquid, and a third washing liquid, from the exit end of said liquids without driving said film at intermediate points, the said film floating through said liquids in submerged position substantially horizontally and out of contact with the containers in which the liquids are held and being guided from one liquid to another, and exposing said film tape to fogging light during its passage between said clearing liquid and said re-developing liquid.

5. The method of producing a positive image on an exposed motion picture film tape that comprises drawing the tape successively through a developing liquid, a washing liquid, a bleaching liquid, a second washing liquid, a clearing liquid, a re-developing liquid, a fixing liquid, and a third washing liquid, from the exit end of said liquids without driving said film at intermediate points, the said film floating through said liquids in submerged position substantially horizontally and out of contact with the containers in which the liquids are held and being guided from one liquid to another, and exposing said film tape to fogging light during its passage between said clearing liquid and said re-developing liquid.

Signed at Universal City, Calif., this 28th day of September, 1931.

CHARLES ROY HUNTER.
